(57) **CLAIM**

The ornamental design for an animated mobile decoy, as shown and described.

DESCRIPTION

FIG. 1 is a perspective view of a first embodiment of an animated mobile decoy showing my new design, with the wings in a closed position;

FIG. 2 is a top perspective view of a second embodiment of an animated mobile decoy, with the wings shown in an open position;

FIG. 3 is a bottom perspective view of FIG. 1;

FIG. 4 is another perspective view of FIGS. 1 and 2, with the head rotated;

FIG. 5 is a rear perspective view of FIG. 1; and,

FIG. 6 is a partial top perspective view of FIGS. 1 and 2, with the wings shown in an open position.

Each embodiment of the invention includes the shell, the anti-tilting means, the skirt, the motor, wheels, the rotatable head, the wings, the lifting means, lighting member, and tail fan.
